(57) **CLAIM**

The ornamental design for a nose guard as shown and described.

DESCRIPTION

FIG. 1 is a perspective view of an ornamental design for a nose guard.

FIG. 2 is an elevation view depicting front, rear, right, and left views of the ornamental design for a nose guard of FIG. 1.

FIG. 3 is a top plan view of the ornamental design for a nose guard of FIG. 1; and,

FIG. 4 is a bottom plan view of the ornamental design for a nose guard of FIG. 1.

In the drawings, the broken lines are for the purpose of illustrating portions of the nose guard, that form no part of the claimed design.

1 Claim, 2 Drawing Sheets
